UNITED STATES PATENT OFFICE.

ALBERT J. ALLISON, OF DAYTON, OHIO, ASSIGNOR TO THE A. A. SIMONDS SONS COMPANY, OF DAYTON, OHIO, A CORPORATION OF OHIO.

BEATER-ROLL.

1,318,949.

Specification of Letters Patent.

Patented Oct. 14, 1919.

Application filed July 21, 1917, Serial No. 182,062. Renewed May 10, 1918. Serial No. 233,791.

To all whom it may concern:

Be it known that I, ALBERT J. ALLISON, residing at Dayton, in the county of Montgomery and State of Ohio, have invented 5 certain new and useful Improvements in Beater-Rolls, of which the following is a full, clear, and exact description.

My present invention embodies certain principles which are found in the device of 10 my pending application Serial No. 166,102, filed May 3, 1917, although it is on the whole a very different structure. The feature common to both devices, and broadly claimed in the former, is that of securing the fly bars 15 to the supporting member or core by resilient means, which insures continuous pressure of the bars against their seats, thus eliminating the possibility of loose bars. In the present invention each bar is secured in 20 place by separate resilient clamping elements, which enables any bar to be removed and replaced without disturbance of any of the other bars. These clamping elements comprise wedges which bear against the 25 supporting member at two considerably separated points, with a tension member bearing on the opposite side of the wedge approximately midway between these two points. The tension members are attached 30 to the inner edges of the fly bars, and driving the wedges home imparts more or less flexure to the wedges, which, by virtue of their resiliency exert a constant pull on the tension members, thus holding the fly bars 35 firmly in the bottoms of radial slots in the supporting member.

The principal object of this method of fastening the bars is to prevent their becoming slightly loose, as so often occurs 40 where they are fastened in the usual way. Another object is to enable any bar to be removed without disturbing the remaining bars in the roll. Another object is to allow for slight inaccuracies in the bars. The 45 wedges being capable of more or less flexure they are able to accommodate themselves to variations in the bars and other parts, yet insuring the bars being tight.

The spaces between the bars are filled by 50 an improved wood filler. These fillers are made in two parts, tapered in opposite directions, so that when put together they form a filler the shape of the space. One object of this construction is to adjust the 55 thickness of the filler, this being done by

driving one part more or less in advance of the other. Another object is to facilitate the insertion of the fillers, especially when, as in the present case, the bars are corrugated.

In the accompanying drawings,

Figure 1 is a sectional elevation of my improved roll.

Fig. 2 is an end elevation of the roll, partly in section.

Fig. 3 is an enlarged fragmental sectional view of the bar fastening device, showing the flexure of the wedge.

Fig. 4 is a fragmental section on line 4—4, Fig. 1.

Fig. 5 is a fragmental section on line 5, Fig. 1.

Fig. 6 is a perspective view of a fly bar.

Fig. 7 is a perspective view of a wood filler.

Fig. 8 is a fragmental view of modified form of bar and hook.

Fig. 9 is an end view of the modification shown in Fig. 7.

Similar numerals designate like parts in all of the views.

The supporting member or core comprises two heads 10 secured to a shaft 11. Between these heads is mounted on the shaft a disk 12 used to support the centers of the fly bars. The heads 10 are provided with slots 13 (see Fig. 4) to receive the fly bars 14. Adjacent to each slot 13 and communicating therewith, is a recess 15 extending down into the head toward the shaft (see Fig. 5), and communicating with said recesses are transverse slots 16. At each end the fly bars are provided with apertures 17, into which is inserted laterally extending lugs 18 formed on one end of bars or rods 19, said bars, which I prefer to call hooks, since their function is analogous to that of a hook, being inserted in the recesses while the bars are inserted in the slots 13. The shanks of the hooks are provided with eyes 20 (so called because of their being at the end of the shanks like the eye of a needle), which when the hooks are in place register with the slots 16. Wedges 21 are then driven into the slots 16, said wedges passing through the eyes 20. As shown in Fig. 3, the wedges bear against the sides of the slots 16 farthest from the shaft at two widely separated points, while the centers of their opposite edges bear against the ends of the 110

eyes, the ends of the eyes being slightly rounded so as to concentrate the bearing. The proportions of the parts are such that driving the wedges into place puts sufficient strain upon them to flex them. This flexure, by virtue of the resiliency of the wedges, puts a powerful tension on the hooks, which being communicated to the fly bars holds them firmly against the bottoms of the slots 5

10 13. It will be noted that the slots 13 are slightly broader at their outer than their inner portions and that the fly bars are wedge shape in cross section. By correctly proportioning the parts the bars may be

15 made to become tight in the slots about the time or even shortly before their inner edges touch the bottoms of the slots. A portion of the tension of the tension members is thus utilized for clamping the bars laterally,

20 thereby insuring firmness in their settings. The slots 13 are not cut through the outer faces of the heads, members 25 being left standing. The ends of the bars are cut away as at 26, making them shorter at their inner

25 than their outer edges, the length of the outer edge being preferably equal to the length of the roll. The members 25 occupy the spaces 26 in the bars and prevent the bars shifting endwise. On the outside of

30 the heads the slots 16 are located in annular channels formed in the heads 10, and after the wedges are in place segmental plates 22 are laid in the channels and fastened with screws, giving the heads a smooth

35 exterior. This is a valuable feature as there is nothing then on the head to catch material contained in the beater engine. These plates or covers are adapted to perform another function, namely, to prevent the

40 wedges 21 from working out. This will be understood by reference to Figs. 1 and 3, where it is seen that the heads of the wedges touch the plates. But as the wedges are not liable to work out, at least no more so than

45 a nut is liable to work off of a bolt, the plates may be regarded as a potential rather than an active safeguard. The bars are fully secured by the clamping devices, and the roll may be used to perform its normal

50 function for an indefinite time without the plates being in place. This function of safeguarding the wedges is somewhat analogous to the function of a nut-lock. For example, it is somewhat like that of a cotter

55 pin run through a hole in the end of a bolt and lying in a groove in the nut. In such cases the cotter pin is generally loose, so that it can be shaken in the hole, but is ready to perform its function in case the nut should

60 start to turn. It is a mere accident that the wedges touch the plates in the drawing, for it is evident that the wedges would perform just the same function if they were driven slightly farther in, so that the plates could

65 not touch them. The wedges extend well

into the interior of the roll, and to remove a bar it is only necessary to remove the wood fillers 23-24 on each side of it, insert a hammer in the space and drive out the wedges. As each wedge and hook is independent of all of the others, and as they react on the head itself; *i. e.*, the same member which carries the bar they secure, driving a wedge in or out does not disturb any part of the assemblage. Wood has been 70 found most satisfactory as a material for the fillers, but some other material, preferably non-metallic, may be used; fiber, for example. The two parts of the fillers are made of such size that when placed together 75 with their edges even, as in Fig. 7, they are the correct size to fill a normal space between the bars. As for various reasons the width of the spaces may vary, the fillers are made in two parts which are tapered in opposite directions. If the space to be filled is undersize the part 24 is put more or less in advance of the part 23 and the thickness 80 of the filler thereby reduced. To fill an oversize space the part 23 is advanced. 85

It is not to be understood that embodiment of my invention must be confined to the structure shown, as various structural modifications are possible within the scope 90 of the appended claims.

What I claim is as follows:

1. In a beater roll; fly bars, a supporting member, and resilient elements for clamping each bar to the supporting member separately, whereby the bars are pressed and held against the supporting member by the tension of their respective clamping elements. 100

2. In a beater roll; fly bars, a supporting member having radial slots to receive the 105 bars, and resilient means for pressing the bars to the bottoms of the slots.

3. In a beater roll; fly bars, a supporting member having radial slots to receive the bars, recesses communicating with said slots, said recesses having shoulders, hooks hooked to the bars and occupying said recesses, said hooks having transverse eyes, and wedges adapted to be driven into said eyes, one side thereof bearing against one end of the eyes, 115 the other side bearing against the aforesaid shoulders, thereby drawing the hooks toward the axis of the roll, so as to hold the fly bars firmly in the slots.

4. In a beater roll; fly bars, a supporting 120 member having radial slots to receive the bars, recesses communicating with said slots, said recesses having shoulders, hooks hooked to the bars and occupying said recesses, said hooks having transverse eyes, and wedges 125 adapted to be driven into said eyes, one side thereof bearing against one end of the eyes, the other side bearing against the aforesaid shoulders, the bearing in the eyes being intermediate the shoulders, thereby tending 130

to flex the wedges as they are driven in and draw the hooks toward the axis of the roll by the tension of the wedges.

5. A beater roll comprising a shaft, two heads secured thereto at suitable distances apart, said heads having radial slots, recesses communicating with the slots and extending toward the shaft, fly bars extending from head to head and seated in the slots, hooks attached to the bars, extending toward the shaft in said recesses, eyes in the shanks of the hooks, transverse slots through the heads in registration with said eyes, and wedges driven through said slots and eyes, bearing at each side of the hook against the side of the transverse slots nearest the fly bars and bearing against the side of the eyes farthest from the fly bar, thereby tending to flex the wedges as they are driven in and draw the hooks toward the axis of the roll by the tension of the wedges.

6. In a beater roll; fly bars, a supporting member, means for securing each bar to the member separately, and fillers composed of two pieces of wood or other material driven between the bars after they are secured to the member; the two pieces of the filler being tapered in opposite directions so that by driving one more or less in advance of the other the thickness of the filler may be varied to suit the space.

7. In a beater roll; fly bars, a supporting member, means for securing the bars to the member, and fillers composed of two pieces of wood or other material filling the spaces between the bars, the two pieces of the filler being tapered in opposite directions so that by placing one or the other closer to the axis of the roll differences in the widths of the spaces may be compensated for.

8. A filler for the spaces between the fly bars of beater rolls comprising two pieces of wood or other suitable material, said pieces jointly having the form of the spaces but being tapered in opposite directions so that by placing one or the other piece closer to the axis of the roll differences in the width of the spaces may be compensated for.

50 9. A beater roll comprising a shaft, two heads secured thereto at suitable distances apart, said heads having radial slots, recesses communicating with the slots and extending toward the shaft, fly bars extending from head to head and seated in the slots, hooks attached to the bars, extending toward the shaft in said recesses, eyes in the shanks of the hooks, transverse slots through the heads in registration with said eyes, said slots being located in annular channels formed in the heads, wedges driven through said slots and eyes, bearing at each side of the hook against the side of the transverse slots nearest the fly bars and bearing against the side of the eyes farthest from the fly bar, thereby

tending to flex the wedges as they are driven in and draw the hooks toward the axis of the roll by the tension of the wedges, and segmental plates to fill the channels in the heads, secured therein with screws, thereby giving the heads a smooth exterior.

55 10. A beater roll comprising a supporting member having radial slots, fly bars mounted thereon with their inner edges in said slots, a plurality of independent radial tension members at each end of the roll whereby the bars are drawn toward the axis of the roll, and means whereby a portion of the tension is utilized to clamp the bars laterally.

11. A beater roll comprising a supporting member having radial slots which are broader at their outer than their inner portions, fly bars mounted thereon with their inner edges in said slots, said bars being wedge shape in cross section so as to be complementary to the slots, and a plurality of radially disposed tension members at each end of the roll, whereby said bars are drawn toward the axis of the roll.

12. In a beater roll; fly bars, a supporting member, means at each end of the supporting member for securing the bars thereto, the means at one end being independent of that at the other end, and removable plates covering said securing means so that particles of the contents of the beating engine can not catch thereon; said securing means being complete in itself and holding the bars so that the roll may be rotated at normal speed and used to perform its function for an indefinite time whether the plates are in place or not.

13. In a beater roll, fly bars, a supporting member, means at each end of the supporting member whereby the bars are fastened thereto, comprising elements which when put in place complete the security of the bars, so that the roll may be rotated at normal speed and used to perform its function for an indefinite time, the means at one end being independent of that at the other, and removable plates whereby the bar-fastening means is covered to prevent particles of the contents of the beating engine catching thereon, said plates being adapted to prevent displacement of the aforesaid elements.

14. In a beater roll, fly bars, a supporting member, means at each end of the supporting member whereby the bars are fastened thereto, comprising elements which when put in place complete the security of the bars, so that the roll may be rotated at normal speed and used to perform its function for an indefinite time, the means at one end being independent of that at the other, and means for preventing the accidental displacement of said elements.

15. In a beater roll, supporting elements carrying abutments and seats for fly bars; fly bars occupying said seats, and clamping

elements detachably secured to the fly bars, said elements comprising resilient members which bear on said abutments in such a manner and with such force as to hold the bars to their seats.

16. In a beater roll, a fly bar having an aperture, a supporting member therefor, a tension member hooked into said aperture, and resilient means for imparting tension to said member, whereby to hold the bar firmly to the supporting member.

17. In a beater roll, a fly bar having an aperture, a supporting member therefor, a beam, a tension member, one end of which is hooked into said aperture, the other end bearing on the beam, and means for applying strain to the beam at points removed from said bearing whereby to put the ten-

sion member in tension and thereby hold the bar firmly to the supporting member.

18. A beater roll comprising fly bars having their ends partly cut away so that at their inner edges they are shorter than at their outer edges, a supporting element comprising two heads fixed on a shaft, each head having seats for a predetermined number of bars and members which occupy the spaces formed by cutting away the ends of the bars, and means for securing the bars to said seats.

In testimony whereof I affix my signature in the presence of two subscribing witnesses.

ALBERT J. ALLISON.
